COMBINATION COLLAPSIBLE SUPPORT
AND CARRIAGE CAGE FOR WASHING
MACHINESSidney S. Holland, Sandusky, Ohio, assignor of
one-half to Oscar Rieger, Sandusky, Ohio

Application May 2, 1935, Serial No. 19,450

4 Claims. (Cl. 248—150)

The present invention relates to a combination collapsible support and carriage cage for washing machines.

Washing machines are made either with a set 5 of legs attached directly to the machine and of sufficient height to support the machine in working position, or with corresponding bases forming a part of the machine. Whether legs or bases, the support and machine together, bring the machine high enough to be in a proper working 10 position. All such machines constitute a separate and distinct piece of equipment which must be allotted corresponding space in a kitchen or wherever used. More recently, some smaller 15 types have been designed. In such types when stands or bases are provided to support the machine at proper working height, as is usual, there are two pieces of equipment for which space must be found. The present invention is intended 20 to avoid the above and other objections in washing machines, especially in the smaller types. It is especially designed for apartment and similar use where every cubic foot is at a premium.

The invention provides a midget or very small 25 size washer of a height which may be readily stowed away beneath a sink or other shelf-like structure, utilizing otherwise waste space. Co-operating with this midget washer is a combination collapsible carriage cage and stand or support. This structure, when opened or spread, 30 constitutes an efficient base or support by which the midget washer is raised to and securely supported in accessible or working position. This same structure, when collapsed, receives the washer as a cage and securely supports it in a lower plane, with the washer feet just clear of the floor. In this position, the structure comprises a roll away wheeled carriage cage for the washer, adapted to be quickly and easily rolled 35 under a sink or other shelf-like structure or to be rolled out from beneath the same, for use, as the case may be.

The combination provides a very simple, efficient and inexpensive midget washing machine 40 of a size especially desirable for apartments, flats and similar places where space is at a premium, with a structure adapted to support it, selectively, in either its raised operative position or in its lowered position and to quickly and easily carry it into or out of an otherwise waste space with the least possible effort. It is simply rolled away and rolled out as desired. The size and weight of the entire washer are such that it is easily picked 45 up and set down, by the user, a pair of simple

grips or handles being provided on the lower part of the outer wall for that purpose.

In order to more clearly disclose the construction, operation and use of the invention, reference should be had to the accompanying drawing 5 forming part of the present application.

Throughout the several figures of the drawing, like reference characters designate the same parts in the different views.

In the drawing:—

Fig. 1 is a side view slightly in perspective showing the washer in supported or working position;

Fig. 2 is a side elevation with washer in carrying position, the washer being shown in dotted lines;

Fig. 3 is a top plan view of Fig. 2, the spread position of the carrier being shown in dotted lines; and,

Fig. 4 is an enlarged fragmentary detail of one corner, broken away to show the roller and its 20 mounting.

The details of the washing mechanism of the washer itself do not enter into the present invention and will not be referred to. The washer, roughly speaking, has a capacity of approximately 25 one-third of that of the regular full size washer. It is, therefore, much smaller in diameter and in height. It is of much less weight. The regular washer legs are entirely omitted. Instead, very short feet, only a few inches in length, are used. 30 So, the total size of the entire washer is such that it may be very easily stowed away under the regular average sink or other shelf-like structure. While not in use, it occupies no otherwise usable space.

Referring to the drawing in detail 1 indicates the midget washer, as a whole. The side wall is extended downwardly to provide a short skirt flange 2 to which the upper ends of the feet 3 40 may be riveted, bolted, welded or otherwise suitably secured. Feet 3 are very short, just long enough to raise the washer from the floor. The whole unit is amply small, in all dimensions, to be easily moved into and out of the space beneath an apartment sink or other small waste space. But, alone, it is entirely too short or low for working position of a user. The present invention combines with this washer, a carriage cage which by a simple swinging movement is collapsed to receive within it the washer for carrying the washer to its out-of-the-way place beneath a sink, and by a reverse swinging movement is spread to stand beneath and provide an efficient support to receive and hold the washer in raised 50 or working position.

The collapsible carriage cage which supports the washer both in raised or working position, and in lowered or carrying position for rolling into and out of storage, preferably, is made from 5 flat strong iron bars. In the construction chosen to illustrate the invention, there are two rectangular frames each substantially a duplicate of the other and pivotally connected at the centers of their top and bottom members. For economy in quantity production, the vertical members 4 of the frames are all the same—simple, straight, flat bars. The end members 5 of all frames are also simple flat bars. Their opposite ends are up-set to provide attaching flanges 6 through which they are riveted, or otherwise suitably secured to the members 4. Each end member is provided with an opening 7 near each end for the free passage of the stem or post 8 of a castor 9 swivelled in and having limited vertical movement in a small bracket or castor casting 10, which is suitably bolted, as at 11, to the respective end member 5. While the bolt 11 connects the casting 10 to its end member 5, the bolt 11 and post 8, together, by engaging 25 the member 5 at different and separated points, maintain the position of casting 10 in alignment with its end member so that it will not swing out to one side or the other and, possibly, be snapped off. Of course, each end member is 30 provided with a perforation or opening 12 near each opening 7 for the bolts 11. At a very short distance inwardly toward the longitudinal center of the bar from each perforation 12, two spaced ears, lugs or stops 13 are punched up or otherwise suitably formed from the metal of the bar. These ears are spaced apart lengthwise of the bar for a purpose to be later disclosed. Between each pair of stops, the respective end member is wrapped or otherwise suitably provided with a protecting cushion, pad or buffer 14 of rubber or other suitable material. This protects both the respective members 5 and skirt flange 2, provides a vibration and sound deadening contact between the washer and carriage cage and furnishes a non-skid surface between 45 these same parts. At intervals along the length of each bar 5, between its longitudinal center and the nearer stop 13 the bar is provided with one or more perforations or openings 15.

50 Two such frames are pivotally connected together through the longitudinal centers of their respective end members in any suitable manner as by pivot rivets 16, bolt and nut or any other well known device. Two frames so pivotally connected may be swung toward or from each other through a considerable arc, as will be readily understood. A pair of these frames constitutes one carriage cage and support or stand. Since members 4 and 5 of each frame are respectively, of the same length, the central portions of the end bars of one frame are inwardly offset or deflected as at 17 to a distance approximately equal to that of the thickness of the member 5. This permits one frame 60 to be passed within the other for pivotal connection between the two frames. It also provides limit stops, as the shoulders 18 formed at each end of each offset will engage the corresponding member 5 of the other frame as the frames approach alignment. The length of the offset is such as to permit the frames to be swung close together before the shoulders 18 engage members 5. This is the collapsed, closed, cage or carrying position. To lock the carriage in this 70 position to receive and carry the washer, a latch 75

19 is provided. One end of this latch is suitably pivoted in any well known manner in one of the perforations 15, of the top bar, preferably, of one frame. Then, when the frames have been swung to collapsed position, the hooked free end 5 is dropped into the opening 12 of the other member 5, locking the frame in closed position. The same latch will equally well securely lock the frames in spread or washer supporting position. For that purpose it is only necessary to raise the 10 latch, swing the frames to positions at right angles to each other and then drop the free end of the latch into the perforation 15 of the other bar, instead of into 12—see Fig. 2.

It will be noticed that the outside diameter of 15 the washer is about equal to the distance between the centres of the two pads 14 on the members 5 and, therefore, slightly less than the inside distance between a pair of the vertical members 4. That diameter is considerably greater than the 20 distance between adjacent members 4 of the two frames when the frames are in spread position at right angles to each other. For that reason the washer cannot be put into its carriage cage when the cage is spread but may be put in when 25 the cage is collapsed, because as the frames approach alignment, in their collapsed position, substantially the full width of the frame is open to receive the washer.

As the washer is set on the pads 14 of the lower 30 members 5, its feet 3 will just properly clear the floor surface. The crossed members 5, give an adequate four-point support for the washer while in the cage and as the carriage with its washer is being rolled away under the sink.

To use the washer, it is only necessary to take hold of any part of the carriage cage, pull it out, lift out the washer, swing the frames to open, spread or washer supporting position, lock them so and set the washer in place with its edge resting 40 on the pads 14 between stops 13 of the top members 5.

It will be obvious that whether the washer is in working position supported on top of the carriage cage or in non-working position within, 45 it is equally supported by the carriage cage, and that the carriage easily and quickly rolls or trundles it to any desired position with least possible effort.

As is well known, there is a certain amount of 50 vibration in every washing machine, causing a tendency to "walk" or move about on the floor. Stops 14, in addition to acting as centering means and guides for placing the washer, also act to check any such tendency and limit any "walking" 55 to the distance between any pair of such stops, as will be clear. Also the rubber pads 14 have a like tendency, as the skirt flange 2 bites into the rubber sufficiently to keep the washer in place under normal conditions. Also, as will 60 be understood, the pads 14 and swiveled castors thoroughly dissipate such vibrations and practically eliminate the "walking" tendency.

A combined carriage cage and support made 65 according to this invention may be packed in with its respective washer, for shipment, with the least possible additional space requirement. The only additional space, if a rectangular package is used, would be a very slight increase in bottom-to-top measure, because the side members of the frame would go into the corners. If, as would 70 probably not be the case, cylindrical packages are used, then a slight increase in width would also be required—equal to the difference between the 75

length of members 5 and the outside diameter of the washer.

By placing the latch between the pivotal center 16 and the stop 13 and having it operate vertically, its positive locking engagement is absolutely maintained at all times during working position of the washer on top of the carriage cage. It is a "fool proof" construction. This assures the best possible support for the washer—a four-point support in which all points are equidistant around the outer wall or circumference. That is the securest possible support against over turning or upsetting while in use. Security in that respect is particularly essential in a small light-weight washer. The bottom of the washer becomes a hold-down for the latch preventing it from becoming disengaged. This is a safety feature resulting from co-operation of washer and carriage cage and completely eliminates the human element in keeping the carriage cage spread for adequate support and safe operation of the washer thereon.

It is believed that the construction, operation and use of the invention will be clear from the preceding detailed description.

Many changes may be made in the construction, arrangement and disposition of the various parts of the invention within the scope of the appended claims without in any manner departing from the field of the invention and it is meant to include all such within this application wherein only one preferred construction has been illustrated as an example and with no intention to any degree limit the invention thereby.

Having thus described my invention, what I claim and desire to protect by Letters Patent is:—

1. A collapsible carriage cage for washing machines comprising two frames pivotally connected one within the other, stops limiting the relative movement of said frames, a latch carried by one of said frames and selectively engaging the other frame to secure said frames spread and collapsed, respectively, end members of said frames adapted to support a washing machine within said cage clear of the floor surface, end members of said frames adapted to support a washing machine on top of said cage in working position, and stops, carried by said last named end members and engaging and limiting lateral movement of a washer.

2. In a collapsible carriage cage for washing machines, two frames each comprising two side bars and two end bars connected together each end bar being provided with pairs of spaced stops near its ends and perforations between its ends and its longitudinal center, means for pivotally connecting one frame within the other through the longitudinal centers of the respective end bars, means carried by an end bar of one frame and selectively engaging the corresponding end bar of the other frame to secure and maintain said frames in spread and collapsed positions, and means carried by the end bars of one frame and engaging the end bars of the other frame to limit relative collapsing movement of said frames. 15

3. In a collapsible carriage cage for washing machines, two frames of same dimensions and each comprising two side bars and two end bars connected thereto, the end bars being provided with pairs of spaced stops near their opposite ends and perforations between their ends and their longitudinal centers, a latch carried by the end bar of one frame and selectively engaging perforations in the corresponding end bar of the other frame to secure and maintain the cage 25 spread and collapsed, means pivotally connecting said frames one within the other through the longitudinal centres of the end bars, the end bars of one frame being offset to permit that frame to pass within the other frame for connection there- 30 to and to provide stops engaging the other end bars and limiting collapsing movement of said frames.

4. A collapsible carriage cage for washing machines comprising two frames pivotally connected together one within the other, stops limiting the relative movement of said frames, a latch carried by one of said frames and selectively engaging the other frame to secure said frames spread and collapsed, respectively, end members of said frames adapted to support a washing machine within said cage clear of the floor surface, end members of said frames adapted to support a washing machine on top of said cage in working position, stops carried by said last named end 45 members and engaging and limiting lateral movement of a washer, and friction pads carried by said end members between said stops.

SIDNEY S. HOLLAND.
